UNITED STATES PATENT OFFICE

HOWARD O. McMILLAN, OF MINNEAPOLIS, MINNESOTA

EXTENSIBLE SHORE

Application filed October 18, 1926, Serial No. 142,212. Renewed June 8, 1931.

This invention relates to a shore such as commonly used for supporting timbers in building construction. The height at which said timbers are supported varies on different building jobs and it is desirable to have a shore which may be extended or adjusted to suit the timbers to be supported. It is also desirable to have means for securely holding the shore in extended position and for moving the supporting part thereof upward into firm supporting position. It is also desirable in a shore to have the relatively movable parts centered in respect to each other or disposed symmetrically about a central axis. It is also necessary from a commercial standpoint to have a shore which is simple in construction, strong and durable and which can be made at comparatively small cost.

It is an object of this invention, therefore, to provide an extensible shore comprising a standard and a timber supporting member movable relatively thereto, which parts are symmetrically disposed about a central axis, together with means for relatively moving said parts and for holding the same firmly in adjusted position.

It is a further object of the invention to provide a shore comprising spaced parallel members securely held in position by suitable spacing means, together with a standard centrally movable between said members, said members having supporting means at their lower ends embracing said standard, and means passing through said last mentioned means and standard for relatively moving the same and said standard and holding the same in fixed position.

It is another object of the invention to provide such a shore as set forth in the preceding paragraph, in which the means supporting said parallel members has a plurality of elongated slots extending therethrough and spaced longitudinally thereof, and in which said standard has a plurality of elongated slots extending therethrough and spaced longitudinally thereof a different distance than the slots in said means, together with wedge members adapted to extend through the slots in said means and standard relatively

adjusting the same and holding the same in adjusted position.

It is still another object of the invention to provide an extensible shore having a pair of spaced parallel members with novel and efficient spacing means holding them in proper relation, together with a standard movable between said parallel members and guided by said spacing means.

These and other objects and advantages of the invention will be fully set forth in the following description in connection with the accompanying drawings, in which like reference characters refer to similar parts throughout the several views and in which:

Fig. 1 is a view in front elevation of the device;

Fig. 2 is a view in side elevation thereof;

Fig. 3 is a horizontal section taken on line 3—3 of Fig. 1, as indicated by the arrows;

Fig. 4 is a horizontal section taken on line 4—4 of Fig. 1, as indicated by the arrows;

Fig. 5 is a horizontal section taken on line 5—5 of Fig. 1, as indicated by the arrows, Figs. 4 and 5 being shown on an enlarged scale;

Fig. 6 is a partial view similar to Fig. 1;

Fig. 7 is a partial view similar to Fig. 2;

Fig. 8 is a horizontal section taken on line 8—8 of Fig. 6, Figs. 6 to 8 also being shown on an enlarged scale; and

Fig. 9 is a view similar to Fig. 4, showing a modification.

Fig. 10 is a horizontal section taken on line 10—10 of Fig. 6.

Referring to the drawings, an extensible shore is shown comprising a standard 10 and while this standard may be of various forms, in the embodiment of the invention illustrated it is shown as made from a standard T bar. The standard 10 has at its lower end a base member 11 secured thereto by a headed and nutted bolt 12 extending through spaced lugs 11a on said member 11, between which the central member of standard 10 is received. The cross member of standard 10 also seats in a groove formed between the lugs 11a and another lug 11b on member 11. The base 11a has a plurality of notches 11c extending into the edges thereof adapted

to receive nails or other securing means holding the shore in place. The central member of standard 10 has extending therethrough a plurality of elongated spaced slots 10a. The 5 movable part of the shore comprises a pair of spaced parallel members 13 and while these members may be variously formed, in the embodiment of the invention illustrated they are shown as made of rectangular timbers such as the common 2 x 4 timbers used in building construction. The members 13 are provided with suitable spacing means or separators 14. While various forms of separators may be used, the one illustrated, which 10 has been found to be very efficient in practice, comprises rectangular plates 14a extending across the ends of the members 13 and being provided with holes through which pass means securing the same to the members 13, such as nails 15. As shown in Fig. 1, the 15 nails 15 and the holes therefor are disposed on lines extending at an angle to the sides of the plates 14a and the holes in the plates 14a at opposite sides of the same member 13 are disposed on lines intersecting each other or extending in opposite directions. The 20 plates 14a have secured thereto as by riveting, the plate 14b having a central portion in contact with one of the plates 14a and secured thereto and having side portions extending along the sides of the member 13 as well as end portions bent at right angles to the side portions and extending in contact with the other plate 14a to which they 25 are also secured. The plates 14b have spaced tongues 14c struck up therefrom which are spaced a distance slightly greater than the thickness of the cross member of the standard 10.

30 The members 13 are surmounted by a top or cross member 16 also shown as made from a rectangular timber which is secured to the members 13 by metal straps 17 extending thereover and along the sides of the members 13, suitable nails or other fastening means 35 being driven through the straps 17 and the members 16 and 13. The member 16 is provided with a plurality of holes 16a adapted to receive nails or spikes which will be driven into the timbers supported by the shore. As 40 shown in Fig. 3, the holes 16a are arranged along lines extending at an angle to the sides of the member 16. A block 18 is also disposed between members 13 immediately 45 below the member 16 and secured to all of said members. The members 13 are supported and connected at their bottoms by a member 19 which preferably is made as a casting and has a horizontal flange extending beneath members 13 and vertical flanges extending at each side thereof, said horizontal flange having apertures 19a therethrough 50 adapted to receive nails or other suitable fastening means 20 extending therethrough and into the bottoms of the members 13. The

horizontal flange also has a T-shaped opening therethrough through which passes T-bar 10. The vertical flanges are apertured to receive the headed and nutted bolts 21 extending therethrough and through the lower ends 55 of member 13, washers 22 being disposed under the heads of said bolts. The member 19 has portions extending longitudinally at each side of the central member of the standard 10 connected by a sleeve 19b at their lower ends entirely surrounding member 10. Said portions have elongated slots 19c extending therethrough, which slots are spaced a different distance apart than the slots in the standard 10 and while the slots 19c may be 60 spaced various distances, they are shown as spaced substantially three times the distance apart as are the slots 10a in member 10. Wedges 23 are provided shown as right-angled in form and of uniform thickness, 65 which wedges have their larger ends considerably wider than the length of the slots 10a and 19c and are adapted to extend through said slots as shown in Figs. 1 and 6. The wedges 23 have holes in one corner for 70 the attachment of flexible members such as the chains 24 secured at their other ends through apertures in the washers 22 which have a portion bent outwardly for this purpose. The member 19 also has lugs 19d projecting at one side thereof in alignment with the slots 19c, which lugs are threaded to receive set screws 25 adapted to engage the wedges 23 when disposed in said slots. The 75 set screws 25 have holes 25a extending through the heads thereof, so that an ordinary wire nail can be placed therethrough and used as a wrench to tighten said set screws.

In Fig. 9 a modified form of spacer or 80 separator 26 for the members 13 is shown. The separator comprises rectangular plates 26a extending across the ends of members 13 and having apertures therein to receive the fastening means 15 as already described in 85 connection with spacers 14. A plate 26b has a central portion riveted or otherwise secured to one of the plates 26a, which is the one adjacent the central member of standard 10. The plate 26b has side portions extending at right angles to said central portion, which side portions extend along the 90 sides of the members 13 and are bent towards each other substantially at right angles at their end portions and secured to the plate 26a in any suitable manner, as by the rivets shown. Tongues 26c are struck up from the side portions of plate 26b and spaced apart a distance slightly greater than the thickness of the cross member of the standard 10, so that said cross member may be removed and be guided therebetween as shown in Fig. 9. The plate 26b also has tongues 26d struck up from its central portion spaced 95 a distance slightly greater than the thickness 100

of the central member of the standard 10, which member is adapted to be disposed between and guided by said tongues 26d.

In operation the wedges 23 are removed, the base 11 placed in the desired position, and the movable section comprising members 13, raised until it is in contact with the timbers to be supported. At this time one of the slots 19c will be partially alined with one of the slots 10a in standard 10. One of the wedges 23 is then inserted through the slots 19c and 10a and driven transversely therethrough. This moves the members 13 and the parts carried thereby further upward, thus firmly positioning member 16 in contact with the supported timbers. The wedge is of such taper that when the standard and movable section have been positioned as desired, the wedge will be held in position by friction. The wedge may be additionally locked in position by tightening the set screw 25 in alinement therewith. The set screws 25 may be tightened by merely placing through the heads thereof an ordinary wire nail of which a supply will be on hand in any building operation. No wrench or special tool is thus required. If it is ever desired to extend or raise the shore under load, this may readily be done by driving in the first wedge until the slots 19c and 10a, through which it passes, are substantially alined. At this time the other slot 19c will be in partial alinement with another slot 10a and the other wedge may be inserted through these slots and driven into place. When these latter slots are brought into alinement, the first slot 19c will again be in partial alinement with another slot 10a and the other wedge may then be inserted and driven into place. The movable section can thus be progressively and successively raised on the standard 10 as desired. The chains 24 are provided so that the wedges will always be on hand with the device and not become lost during transportation. The standard 10 moves between the members 13 and is guided in the spacing members 14. The transverse member of the standard moves between the tongues 14c and is guided thereby. If the spacer shown in Fig. 9 is used, both the central and transverse members of the standard are guided, the central member moving between and being guided by tongues 26d. It will be noted that there are no horizontal plates extending between the members 13 on which concrete might collect. The spacing members 14 have their edges disposed upward so that the plates are in vertical planes and any concrete will drop past the separators 15 and not accumulate thereon. The nails 15 at the opposite sides of the members 13 being disposed on lines extending at an angle to each other, add strength to the device and this arrangement tends to prevent twisting. The separators 14 are very stiff and rugged.

in construction and hold the members 13 securely in properly spaced relation.

The straps 17 are provided so that when the shore is taken down, the member 16 will not be pulled off of the members 13 by the fastening means extending through the holes 16a. The member 16 is, of course, tightly nailed to the members supported thereby and must be pulled loose therefrom.

It will be noted that the shore is quite symmetrical, the central plane passing through the central member of standard 10 also being the central plane between the members 13. The central axis of slots 10a also lies in the plane extending centrally and transversely of the members 13. The load is carried on the wedges 23 and is thus carried centrally of the device so that there is no eccentric or twisting action on the shore due to the load.

From the above description it is seen that applicant has provided a very simple, efficient, durable and inexpensive shore, and one which can be properly extended for use and if desired, adjusted under load. The parts of the device are quite few, the device is easily and quickly operated and no special tools are necessary in the operation thereof. The shore has been amply demonstrated in actual practice and found to be very successful and is being commercially made and marketed.

What is claimed is:

1. An extensible shore having in combination, a movable section comprising spaced parallel bars and a member supporting and connecting said bars at their lower ends, having a portion extending below said bars with spaced sides, said sides having extending therethrough longitudinally spaced alined elongated slots, a standard movable between said bars having a portion extending between said sides, said portion having a plurality of longitudinally spaced elongated alined slots extending therethrough, differently spaced from the slots in said sides, a base on said standard, and a member adapted to pass through slots in said sides and standard relatively to move said section and standard and hold the same in adjusted position.

2. An extensible shore having in combination, a movable section comprising spaced parallel bars, a standard for supporting said section and movable between said bars, said bars being disposed symmetrically about the central axis of said standard, a member secured to and supporting said bars having portions at each side of said standard with a plurality of alined elongated slots spaced longitudinally thereof and extending therethrough, said standard having a plurality of spaced elongated alined slots extending therethrough, differently spaced from the slots in said portions, a vertical plane passing centrally and longitudinally through said slots passing centrally through said bars.

3. An adjustable shore having in combination, a movable member comprising spaced parallel bars having adjacent flat inner sides, rigid spacing and bracing members extending across opposite sides of said bars and secured thereto, said members having portions extending between said bars parallel to and substantially in contact with said inner sides and carrying inwardly extending portions 70
- 10 forming guide means for said standard, said standard being of T-shape in cross section, said last mentioned portions being disposed at either side of the ends of the cross member of said T.
- 15 4. An adjustable shore having in combination, a movable section comprising spaced parallel bars, rectangular in cross section, a standard movable between said bars and of T-shape in cross section, a rigid spacing and 75
- 20 bracing member for said bars having opposite plate-like sides extending across and secured to the opposite sides of said bars and having plate-like portions extending between said bars, said latter portions having projections 80
- 25 disposed at the sides of the ends of the cross member of said T shaped standard forming guide means therefor.
5. An extensible shore having in combination, a movable section comprising spaced 85
- 30 parallel bars and a member supporting and connecting said bars at their lower ends having a portion extending below said members with spaced sides, a standard movable between said sides and said bars and symmetrically disposed about an axis extending centrally and longitudinally between said bars and means passing through said sides and said standard for relatively moving the same and for holding said section and standard 90
- 35 in adjusted position.
6. An extensible shore having in combination, a movable section comprising spaced parallel bars and a member supporting and connecting said bars at their lower ends having a horizontal flange and vertical flanges 95
- 40 extending therefrom at each side of each of said bars, means securing said bars to said flanges, said member having spaced sides extending below said horizontal flange, a standard having a base at its lower end and 100
- 45 movable between said bars through said horizontal flange and between said sides and means passing through said sides and standard adapted to hold said section and standard in adjusted position, and movable transversely thereof relatively to move said section and standard.
7. An extensible shore having in combination, a standard having a base portion, a member guided for movement longitudinally of said standard and having portions extending above and at either side thereof adapted to support the load centrally of said standard, spaced slots extending through said member and standard, and spaced respec- 105
- tively different distances therein, and members passing through the slots in said standard and member for relatively moving the same, and holding the same in adjusted position.
8. An extensible shore having in combination, a member including spaced parallel portions, means for holding said portions in properly spaced relation, a member guided between said portions for movement longitudinally of said first mentioned member, spaced alined slots extending through one of said members, a slot extending through the other of said members, and means passing through said slots in both members and engaging the other of said members relatively to move said other member and hold the same in adjusted position.
9. An extensible shore having in combination, a movable section comprising spaced parallel bars, a member supporting and connecting said bars at their lower ends, said member extending below said bars and having spaced portions, said member having extending through said portions longitudinally spaced alined elongated slots, a standard member movable between said bars and extending between said portions, said standard member having a plurality of longitudinally spaced elongated slots extending there- 110
- 10 through, and slots in one of said members being spaced a distance less than half the distance the slots in the other member are spaced and the slots in both members being of substantially the same length, and wedge members adapted to be passed through the slots in both members for relatively moving said members, whereby a continuous step-by-step relative movement of said members may be had.
10. The structure set forth in claim 1, and means engaging said last mentioned member to prevent movement thereof relatively to said first mentioned member.
11. An extensible shore having in combination, a movable section comprising spaced parallel bars, a member supporting and connecting said bars at their lower ends, having a portion extending below said bars and disposed centrally thereof, said portion having spaced sides and said member having an opening alined with the space between said sides and substantially of T-shape in plan, a T-shaped standard extending between said sides through said opening and upward between said bars, said sides having spaced elongated slots therethrough respectively alined therein, said standard having spaced elongated slots therethrough adapted to aline transversely with the slots in said sides, the slots in one of said parts being spaced less than half the distance of the slots in the other, and wedges adapted to be driven through said slots in said sides and stand- 115
- 120
- 125
- 130

ard relatively to move said standard and member.

12. An extensible shore having in combination, a movable section comprising spaced parallel timbers, a member adapted to be secured to said timbers at their lower ends and support the same, said member having a depending portion having a central plane disposed substantially coincident with the plane 50 passing centrally between said timbers, said portion having a vertical slot extending therethrough, a metal standard adapted to extend through said slot having a web, the central plane of which substantially coincides with said planes, said depending portion and said web having a plurality of longitudinally spaced slots extending therethrough, said slots being spaced differently in said members, the longitudinal center lines 15 of said slots being disposed substantially in the vertical plane extending transversely and centrally of said timbers.

13. In combination with an adjustable shore, comprising spaced parallel bars, having adjacent flat inner sides, and a standard of T-shape in cross section movable between said bars, a spacing and bracing member comprising plates rigidly secured to and extending between the outer sides of said bars 25 which are at right angles to said inner sides, and plates rigidly connected to said plates and extending along said flat inner sides, said lateral plates having spaced parallel portions extending toward each other on said 30 respective plates and in transverse alinement, all of said plates being disposed in vertical planes, said projecting portions forming guides for the sides of said standard.

14. In combination with an adjustable shore, comprising a movable member having spaced parallel timbers rectangular in cross section with their long sides adjacent, and a standard having oppositely projecting flanges movable between said timbers, a rigid 45 spacing and bracing member having plates secured to and extending between the shorter sides respectively of said timbers, and connected by plates extending along the adjacent sides of said timbers, said lateral plates having spaced parallel portions struck up therefrom and in transverse alinement on the respective plates forming guides for the flanges of said standard, all of said plates being disposed in vertical planes.

15. In combination with an adjustable shore, comprising a movable member formed of spaced parallel timbers rectangular in cross section, and a standard of T-shape in cross section movable between said timbers, a rigid 50 spacing and bracing member having spaced parallel plates secured to the shorter sides of said timbers and extending respectively therebetween, a plate bent into substantially rectangular shape and secured to said last mentioned plates and extending flat along the

adjacent sides of said timbers, said latter plate having inwardly projecting portions at opposite sides forming guides for the sides of said standard, all of said plates being disposed in vertical planes.

16. An extensible shore having in combination a movable section comprising spaced parallel bars and a member supporting and connecting said bars at their lower ends having a portion extending centrally below said members with spaced sides, a standard having a portion movable between said sides and said bars, said sides and portion of said standard having elongated slots therethrough differently spaced in said sides and portion of said standard and arranged to aline, a wedge adapted to pass through said slots and relatively move said sides longitudinally, and means for locking said wedge in position.

17. An adjustable shore having in combination, a movable section comprising spaced parallel bars, a member supporting and connecting said bars at their lower ends, said member extending below said bars, a supporting standard extending between said bars and passing through said member, and a wedge movable transversely of said member and acting in cooperation with said standard to hold said member and bars in position.

18. An adjustable shore having in combination, a movable section comprising spaced parallel bars and a member supporting and connecting said bars at their lower ends, a supporting standard having a base portion at its lower end and extending upwardly between said bars, said member having transversely extending openings therein, and a wedge movable transversely through said openings for holding said member and bars in fixed position with said standard acting as a support.

19. An adjustable shore having in combination, a movable member comprising spaced parallel timbers, a rigid member on which the lower ends of the timbers rest having flanges extending along the sides of said timbers and secured thereto, said member having a portion disposed below said lower ends substantially centrally of said bars and having an opening extending transversely therethrough, a supporting standard extending upwardly through said member and between said bars, and a wedge adapted to be driven through said opening to hold said bars and member in position with said standard acting as a support.

20. An adjustable shore having in combination, a pair of spaced parallel bars, means connecting said bars at their tops and adapted to carry the load, a standard forming a support for said shore having a base portion and extending upwardly between said bars, a member supporting said bars at their lower ends and embracing said standard, said standard having a series of transverse slots there-

through for determining the position of said member, and wedge means cooperating with said member to hold said member in fixed position relatively to said standard.

- 5 21. An adjustable shore having in combination, a pair of spaced parallel bars, a standard of T-shape in horizontal cross section and having a base portion, said standard extending upwardly between said bars, a member supporting the lower ends of said bars extending about said standard and slidably thereon, said member having a transverse opening therethrough below said bars, said standard having a series of slots in the stem portion of said T for determining the position of said member, and means cooperating with said slots and including a wedge adapted to be driven through said opening in said member to hold said bars and member in position with said standard acting as a support.

22. An adjustable shore having in combination, a pair of spaced parallel timbers rectangular in horizontal cross section, a standard having a base portion and an upstanding portion of T-shape in horizontal cross section, said standard extending between said timbers, a member connecting and supporting the lower ends of said timbers and having an opening therethrough through which said standard extends, said standard having a series of transverse openings in the stem-portion of said T, said member having a transverse opening therethrough and a wedge passing through said opening and cooperating with said openings in said standard to hold said timbers and member in position with said standard acting as a support.

23. An adjustable shore having in combination, a movable section comprising spaced parallel bars, a member supporting and connecting said bars adjacent their lower ends, a standard having a base at its lower end and extending upwardly between said bars and through said member, and means extending transversely through said member and cooperating with said standard to hold said member and bars in fixed position relatively to said standard.

In testimony whereof I affix my signature.
50 HOWARD O. McMILLAN.
